UNITED STATES PATENT OFFICE

93,056

DESIGN FOR A BRAKE EXTENSION LEVER

Joel R. Therp, West Allis, Wis., assignor to The Fulton Company, West Allis, Wis., a corporation of Wisconsin

Application September 25, 1933, Serial No. 49,334

Term of patent 3½ years

To all whom it may concern:

Be it known that I, JOEL R. THORP, a citizen of the United States, residing at West Allis, in the county of Milwaukee and State of Wisconsin, have invented a new, original, and ornamental Design for a Brake Extension Lever, of which the following is a description, reference being had to the accompanying drawing, forming part thereof.

In the drawing, Fig. 1 is a side elevation of the brake extension lever showing my new design;

Fig. 2 is a top plan view of the lever, and Fig. 3 is a perspective view on a reduced scale showing the design as it appears when in actual use.

I claim:

The ornamental design for a brake extension lever, substantially as shown and described.

JOEL R. THORP.
